(57) **CLAIM**

The ornamental design for a contact for an electrical connector, as shown and described.

DESCRIPTION

FIG. 1 is a bottom perspective view of a contact for an electrical connector showing our new design;

FIG. 2 is a top perspective view thereof;

FIG. 3 is a top perspective view thereof, in use condition;

FIG. 4 is a bottom perspective view thereof;

FIG. 5 is a side elevation view thereof;

FIG. 6 is a top plan view thereof;

FIG. 7 is a bottom plan view thereof;

FIG. 8 is a front elevation view thereof; and,

FIG. 9 is a back elevation view thereof.

The broken line in the drawing views represents unclaimed environment only, and forms no part of the claimed design.
